UNITED STATES PATENT OFFICE.

HENRY K. GILBERT, OF CHICAGO, ILLINOIS.

ANTICREEPER.

No. 858,973.

Specification of Letters Patent.

Patented July 2, 1907.

Application filed November 14, 1906. Serial No. 343,330.

To all whom it may concern:

Be it known that I, HENRY K. GILBERT, a citizen of the United States, residing at Chicago, in the county of Cook and State of Illinois, have invented certain new and useful Improvements in Anticreepers, of which the following is a specification.

My invention relates to anti-creepers for rails, and has for its objects; to provide a device which will grip the flange of the rail in a very secure manner; to provide a device which may be conveniently and expeditiously applied to the rail; to provide a device in which the strain is largely removed from the clamping bolt; to provide a device adapted to engage the holding tie over an extended surface; and finally, to provide a device of inexpensive construction, of minimum weight and great simplicity. One form of the invention is shown in the accompanying drawings in which

Figure 1 is a transverse section through a rail showing my creeper as applied thereto;

Figure 2 is an end view of the creeper looking from the right of Figure 1, and shows such creeper in position against the holding tie, and

Figure 3 is a section on the line III—III of Figure 1. Referring to the drawing, it will be seen that the device is composed of two clamping members, 1 and 2, which members are provided with hooks 3 and 4 for engaging the flanges of the rail, and these members are secured together by means of the bolt 5. The hook 3 on the member 1 has its sides inclined to each other at an angle slightly more acute than the angle formed by the sides of the flange, whereby when the member is in the position shown in Figure 1 the hook 3 tightly clamps the flange of the rail, which clamping action is accentuated by the provision of teeth 6 (Figure 3) for engaging and biting into the upper surface of the flange. In order to strengthen the clamping member 1 and also to secure an extended bearing surface of such member against the tie 7, the rib 8 is provided, which rib is preferably made in the shape shown in Figure 1. As clearly shown in Figure 1, the left hand end of the member 1 is provided with the toothed surface 9 for engaging a corresponding surface on the member 3, so that when the two members are clamped together by the bolt 5, the shearing strain on such bolt 5 is removed, due to the interlocking of the teeth. An important feature of the invention resides in the disposition of the hook 3 on the member 1. This hooked member 3, as above stated, is provided on its under face with transversely extending teeth 6, and, as indicated in Figure 2, the hook is canted forwardly, thus bringing the teeth on such hook at a slight angle to the axis of the rail. If the tendency of the rail is

to creep in the direction of the arrow in Figure 2, it will be seen that such movement against the inclined teeth on the member 3 will tend to move such member toward the center of the rail, thus clamping the rail still more securely. It will be noted that the bolt 5 is upwardly inclined with respect to the horizontal, so that when the nut is tightened the members 1 and 2 will not only be moved laterally towards each other, but the member 4 will be moved downwardly, due to the component of force in that direction, because of the slant of the bolt. This gives a very effective clamping at the flange engaged by the hook 4.

Having thus described my invention and illustrated its use, what I claim as new and desire to secure by Letters Patent, is the following.

1. An anti-creeper for rails comprising a clamping member adapted to engage one flange of the rail and extend across the bottom of the rail, and a second clamping member adapted to engage the other flange of the rail and abut against the end of the first member, together with means for securing the members together. 70

2. An anti-creeper for rails comprising transverse clamping members engaging the rail flange, one of which members is provided with transverse teeth and is canted in the direction of the tendency of the rail to creep. 75

3. An anti-creeper for rails comprising transverse clamping members engaging the rail flange, which members are provided with transverse teeth and one of which members is canted in the direction of the tendency of the rail to creep. 80

4. An anti-creeper for rails comprising a clamping member adapted to engage one flange of the rail and provided with a flange portion extending across the bottom of the rail, and a second clamping member adapted to engage the other flange of the rail and abut against the end of the first member, together with means for securing the members together. 85

5. An anti-creeper for rails comprising a clamping member adapted to engage one flange of the rail and provided with a toothed portion extending across and downwardly below the rail, and a second clamping member adapted to engage the other flange of the rail and provided with a toothed portion for engaging the teeth on the first member, together with a bolt for holding the toothed surfaces together. 95

6. An anti-creeper for rails comprising a clamping member adapted to engage one flange of the rail and provided with a toothed portion extending across and downwardly below the rail, and a second clamping member adapted to engage the other flange of the rail and provided with a toothed portion for engaging the teeth of the first member, together with a bolt upwardly tilted from the horizontal for drawing the second clamping member against the rail flange and for holding the toothed surfaces together. 105

In testimony whereof I have hereunto signed my name in the presence of the two subscribed witnesses.

HENRY K. GILBERT.
